DESIGN FOR AN ADDING MACHINE CASE

Max Garbell, Chicago, Ill., assignor to Victor Adding Machine Company, Chicago, Ill., a corporation of Delaware

Application April 2, 1937, Serial No. 68,514

Term of patent 14 years

To all whom it may concern:

Be it known that I, Max Garbell, a citizen of the United States of America and a resident of Chicago, Cook County, Illinois, have invented a new, original, and ornamental Design for an Adding Machine Case, of which the following is a specification, reference being had to the accompanying drawing, forming a part thereof.

I claim:

The ornamental design for an adding machine case, substantially as shown.

MAX GARBELL.
